UNITED STATES PATENT OFFICE.

EFFINGHAM C. DUN, OF VISTA ALEGRE, SANTIAGO, CUBA.

EVAPORATING-ACCELERATOR.

1,110,752.

Specification of Letters Patent. Patented Sept. 15, 1914.

Application filed May 3, 1911. Serial No. 624,731.

To all whom it may concern:

Be it known that I, EFFINGHAM C. DUN, subject of the King of England, residing at Vista Alegre, Santiago, Cuba, have invented 5 certain new and useful Improvements in Evaporating-Accelerators, of which the following is a specification.

In sugar factories and refineries, and industries of a like nature where exhaust steam is utilized for the purpose of evaporating the water from the juices, considerable difficulty is occasioned in getting rid of the air which is always present in the steam, but can not be condensed with the same.

When high pressure steam is used in an evaporator or like device it becomes necessary to adopt some means for preventing the steam from flowing out too quickly, and a trap is frequently employed for this purpose, but in an ordinary trap only the water is allowed to pass off and no provision is made for the air. In the case of exhaust steam, or steam at a very low pressure, a trap merely retards the escape of the water 20 and causes the air to accumulate within the pipes in such a manner as to prevent the steam from entering the evaporator and produce a back pressure which materially interferes with the proper working of the machinery and engines.

This apparatus is intended to be utilized as an auxiliary to an evaporator of any approved construction or any similar device, and aims to increase the efficiency of the 35 said evaporator by providing a novel and effective device for exhausting the water and air where steam is utilized for heating purposes. The device will be found of special value where exhaust steam is used for the 40 purpose of concentrating a solution by the evaporation of the water in the solution as in single, double, triple, and quadruple effects, vacuum pans and similar apparatus.

For a full description of the invention and 45 the merits thereof and also to acquire a knowledge of the details of construction and the means for effecting the result, reference is to be had to the following description and accompanying drawings, in which:

50 Figure 1 is a vertical sectional view through the device, the float being shown in an elevated position. Fig. 2 is a similar view showing the float in a depressed position. Fig. 3 is an enlarged sectional view 55 on the line 3-3 of Fig. 2.

Corresponding and like parts are referred

to in the following description and indicated in all the views of the drawings by the same reference characters.

Specifically describing the embodiment of the invention shown in the drawings the numeral 1 designates the shell which in the present instance has a cylindrical formation and is supported in a slightly elevated position by means of the legs 2. Arranged 60 within the shell 1 is a float 3 which is designed to reciprocate vertically within the shell and is shown as having a shallow cylindrical formation. A tube 4 communicating with the interior of the float 3 projects 65 upwardly from the latter member and passes freely through a packing gland 5 at the upper end of the shell. The extremity of the tube 4 is provided with a check valve 6 designed to admit the entrance of air into the 70 tube but to prevent the passage of air out of the tube. A strainer 7 formed of fine wire gauze is carried by the tube 4 and serves to protect the valve 6 and exclude 75 dust and foreign matter from the same. The 80 bottom of the float 3 is provided with a plurality of openings controlled by the valves 8 operating within the float and normally held upon their seats by the action of gravity. Each of these valves is provided 85 with a stem 9 extending through the valve opening and projecting downwardly below the bottom of the float, and also with an upwardly extending stem 10 coöoperating 90 with a guide member 11 to direct the valve in its movement. Projecting upwardly from the bottom of the shell 1 are the lugs 12 which serve to prevent the float from coming 95 into contact therewith. It will be readily apparent however that when the float rests upon these lugs the downwardly extending stems 9 of the valves will engage the bottom of the shell so as to lift the valves 8 from their seats and establish communication 100 between the interior of the float and the shell. Suitable stops 13 are utilized for limiting the upward movement of the float and lateral projections 14 are carried by the float and engage the interior walls of the shell to keep the float centrally disposed 105 therein.

Extending around the interior of the shell or receiver 1 is a hollow annular member 15 communicating with a pipe 16 leading from the evaporator or like device and serving to 110 convey water and air from the same to the receiver. In the preferred embodiment of

the invention the member 15 is a perforated pipe which extends around the interior of the shell and serves to distribute the water and air uniformly within the shell. Interposed in the length of the pipe 16 and 5 preferably located near the receiver or shell is a valve 17 which is designed to be controlled by the pressure within the receiver and is so constructed as to be automatically closed when the pressure exceeds a predetermined amount. As shown on the drawings the upper portion of the casing for the 10 valve 17 communicates with the interior of the receiver through a pipe 18 and the pressure within the receiver operates against a piston 19 controlling the valve 17, the piston being normally held in an elevated position with the valve open by means of a spring 20. However, as soon as the pressure exerted upon the piston becomes sufficient to 15 counteract the spring 20 the piston will be forced downwardly and the valve closed.

Leading from the bottom of the receiver 1 is a pipe 21 through which the water within 20 the receiver is withdrawn therefrom by a pump 22 which may be of any approved construction, the water being discharged at any desired point through the delivery pipe 23. In the present instance the pump 22 is 25 of the duplex type and is operated through the medium of steam or other motive fluid received through a pipe 24, the exhaust from the pump being discharged through the pipe 25. A water gage 26 of any suitable size and make is applied to the receiver 30 and serves to show the height of water within the same. It will also be observed that a combined pressure and vacuum gage 27 is utilized to indicate whether the interior of 35 the receiver is under pressure or in the condition of a partial vacuum.

Communicating with the upper portion 40 of the receiver or shell is a pipe 28 leading to a vacuum pump, condenser or exhausting apparatus of any approved type for withdrawing the air from the shell. A valve 29 is interposed in the length of the pipe 28, the said valve being of the rotary plug type and being actuated by an arm 30 which has 45 an operative connection with the upper end of the tube 4 carried by the float 3. The various parts are so arranged that when the float 3 is depressed and rests upon the lugs 12 the valve 29 is opened and the suction 50 within the pipe 28 operates to withdraw the air from the receiver and produce a partial vacuum therein. As the float is elevated the valve is gradually closed and the effect 55 of the suction within the pipe 28 gradually diminishes until the float reaches the limit of its upward movement when the valve is entirely closed. A second valve 31 is also interposed in the length of the suction pipe 60 65 28 and is designed to regulate the vacuum created within the receiver. This valve 31

opens inwardly and is connected to one end of a lever 32, a weight 33 being adjustably mounted upon the opposite end of the lever and operating to normally hold the valve in a closed position. As soon as the vacuum 70 produced within the receiver causes the pressure therein to fall below a predetermined point the atmospheric pressure upon the valve 31 forces the same inwardly and air enters the receiver so as to reduce the vacuum 75 therein, the valve being again automatically closed through the action of the weight 33 when the pressure within the receiver becomes sufficient to again move the valve 31 against its seat. It will thus be apparent 80 that this valve operates automatically to maintain an approximately uniform vacuum within the receiver under normal working conditions.

Interposed in the length of the steam pipe 85 24 through which motive fluid is delivered to the pump 22 is a valve 34 which is of the rotary plug type and is designed to be actuated through the medium of an arm 35 which is connected in any suitable manner 90 as by the chain 36 to a similar arm 37 rigid with the valve 29. It will also be observed that a weight 38 is pendent from the arm 35 and is connected thereto by a chain or cable 39. The weight is capable of being increased 95 or decreased as required, or if found desirable may be entirely dispensed with and a spring substituted therefor. A second valve 40 designed to be manually actuated is also applied to the pipe 24 for regulating 100 the supply of motive fluid to the pump.

The invention also contemplates means for condensing any steam which might enter the receiver, and for this purpose a second perforated pipe 41 is provided which extends 105 around the interior of the shell above the perforated pipe 15 and communicates with a supply pipe 42 through which cold water is conveyed to the receiver, the said cold water being discharged in the form of a 110 spray through the perforations of the pipe 41. A valve 43 which is normally closed controls the supply of cold water to the receiver.

The apparatus as previously mentioned is 115 designed to be in communication with an evaporator for the purpose of increasing the efficiency of the same and when in operation the pipe 16 communicating with the perforated annular pipe 15 within the receiver is 120 connected to the evaporator so as to receive the water and air discharged from the same as the steam is condensed. Assuming the float 3 to be depressed and resting upon the lugs 12 with the valve 17 open and the valve 125 43 closed, the float in its downward movement will have operated through the arm 30 to open the valve 29 so the suction within the pipe 28 tends to produce a vacuum within the receiver, and will also have operated 130

through arms 35 and 37 connected by the chain 36 to close the valve 34 and shut off the supply of steam or motive fluid to the pump 22. The partial vacuum within the receiver will then serve to draw the water and air from the evaporator through the pipe 16 and will also draw a certain amount of air through the tube 4 and float 3 owing to the fact that when the float is depressed the stems 9 of the valves 8 engage the bottom of the receiver and lift the valves from their seat. The object of this is to free the float of any water which might have found its way into the same, and by having the float open to the atmosphere the air cannot be withdrawn therefrom with the consequence of causing the water to accumulate therein. The air drawn into the receiver through the pipe 16 is exhausted through the suction pipe 28 while the water falls upon the bottom of the receiver and tends to elevate the float. As the float is thus lifted from the bottom of the shell the valves 8 drop upon their seats so as to shut off communication between the interior of the float and the receiver, and the arm 30 which has an operative connection with the tube 4 is caused to slowly close the valve 29, thereby reducing the volume of air exhausted through the suction pipe 28. At the same time the valve 34 interposed in the length of the steam pipe 24 leading to the pump 22 is slowly opened through the action of the arms 35 and 37 which are connected by the chain 36, and the weight 38. As soon as steam is admitted to the pump the same operates to withdraw the water from the bottom of the reservoir and discharge it through the delivery pipe 23. It will thus be apparent that as the float rises the exhaust of air is gradually reduced while the amount of steam delivered to the pump is gradually increased and the action thereof in withdrawing the water from the reservoir correspondingly increased. Upon the fall of the float exactly the reverse condition is established and it will be obvious that there must be a point where a state of equilibrium will be established between the two functions. With this construction the level of water within the receiver is automatically maintained at a predetermined point and the partial vacuum formed therein is automatically retained at a uniform pressure.

For the purpose of giving warning should the receiver be at any time subjected to pressure a whistle 44 is utilized, the said whistle being so arranged as to blow or give warning when the pressure within the interior of the receiver exceeds the atmospheric pressure, but to otherwise remain mute.

Should the steam not be entirely condensed by the evaporator and be drawn into

the receiver, the said steam can be readily condensed by opening the valve 43 and permitting cold water to enter the perforated pipe 41 which discharges it in a fine spray. It will thus be apparent that when the herein-described device is connected to the tail pipe of a pan or evaporator, both the air and condensed steam will be withdrawn and the efficiency of the evaporator thereby greatly increased.

Having thus described the invention, what is claimed as new is:

1. A receiver having a fluid inlet and a fluid outlet, and a float within said receiver having a valve controlled communication between the interior of the receiver and the interior of the float and a valve controlled communication between the interior of the float and the exterior of the receiver.

2. In a device of the character described, the combination of a receiver provided with an inlet, a float arranged within the receiver, a tubular stem carried by the float and establishing communication between the interior thereof and the exterior of the receiver, a valve controlling the communication between the interior of the float and the interior of the receiver, and means for withdrawing air from the receiver.

3. In a device of the character described, the combination of a receiver provided with an inlet, a float arranged within the receiver, a tubular stem establishing communication between the interior of the float and the exterior of the receiver, the said float having an opening in the bottom thereof, a valve controlling the opening and provided with means whereby it is moved from its seat when the float is depressed, means for withdrawing air from the receiver, and means for withdrawing water from the receiver.

4. In a device of the character described, the combination of a receiver provided with an inlet, a float arranged within the receiver and having an opening in the bottom thereof, a tubular stem carried by the float and establishing communication with the interior of the same and the exterior of the receiver, a check valve in the tubular stem permitting the entrance of air but preventing the outflow thereof, a valve controlling the opening in the bottom of the float, the said valve being provided with a stem by means of which it is lifted from its seat when the float is depressed, means for withdrawing air from the receiver, and means for withdrawing water from the receiver.

5. In a device of the character described, the combination of a receiver provided with an inlet, a float arranged within the receiver and provided with a valve controlled opening which is automatically opened at a predetermined position of the float, a tubular stem carried by the float and estab-

lishing communication between the interior thereof and the exterior of the receiver, means for withdrawing air from the receiver, valve controlled means for withdrawing water from the receiver, and an operative connection between the tubular stem of the float and the means for withdrawing air and water.

6. A device of the character described, 10 including a receiver provided with an inlet, a float arranged within the receiver, a tubular stem carried by the float and communicating with the interior thereof and with the exterior of the receiver, a check 15 valve in said stem permitting the entrance of air but preventing the outflow thereof, a valve controlling the communication between the interior of the float and the interior of the receiver, and means for withdrawing air from the receiver.

7. A device of the character described, 20 including a receiver having an inlet through which air and water may enter the receiver, valve controlled means for withdrawing water from the receiver, valve controlled means for withdrawing air from the receiver, a float mounted in the receiver, and formed with an opening establishing communication between the interior of the float 25 and the interior of the receiver, a tubular stem connected to said float and extending upwardly from the receiver, said stem establishing communication between the interior of the float and the exterior of the receiver, 30 a check valve in the outer end of said stem designed to admit air into the stem and to prevent the outflow thereof, and operative connections between said stem and the valves of the air and water withdrawing 35 means.

40 8. A device of the character described,

including a receiver provided with an inlet through which air and water can enter the same, valve controlled means for withdrawing air from the receiver, valve controlled means for withdrawing water from the receiver, a float within the receiver, means actuated by the rise of the float for automatically closing the valve of the air withdrawing means and opening the controlling valve of the water withdrawing means, said means including means independent of the float tending at all times to open the valve controlling the water withdrawing means.

5. A device of the character described, 55 including a receiver provided with an inlet through which air and water can enter the same, valve controlled means for withdrawing air from the receiver, valve controlled means for withdrawing water from the receiver, a float within the receiver, means actuated by the rise of the float for automatically closing the valve of the air withdrawing means, means independent of the float at all times tending to open the controlling valve of the water withdrawing means, and a connection between the two valves whereby the closing of the valve controlling the air withdrawing means will permit the opening of the valve controlling the water withdrawing means, said connection being detachable from its operative engagement with the valve for controlling the withdrawal of air whereby to permit the independent movement of the valve controlling the water withdrawing means.

60 In testimony whereof, I affix my signature in presence of two witnesses.
